UNITED STATES PATENT OFFICE

115,402

DESIGN FOR A CLIP PIN OR SIMILAR ARTICLE

Jules Hirsch, New York, N. Y.

Application March 18, 1939, Serial No. 83,658

Term of patent 3½ years

To all whom it may concern:

Be it known that I, Jules Hirsch, a citizen of the United States of America, residing in the city of New York, county of New York, and State of New York, have invented a new, original, and ornamental Design for a Clip Pin or Similar Article, of which the following is a specification, reference being had to the accompanying drawing, forming part thereof.

Fig. 1 is a plan view of a clip pin or similar article showing my new design.

Fig. 2 is an edge view thereof.

I claim:

The ornamental design for a clip pin or similar article, substantially as shown.

JULES HIRSCH.
